UNITED STATES PATENT OFFICE.

JOSEPH HIRN, OF CHILlicothe, ASSIGNOR OF ONE-HALF TO CHARLES H. NEIL, OF COLUMBUS, OHIO.

CAR-COUPING.

SPECIFICATION forming part of Letters Patent No. 331,639, dated December 1, 1885.

Application filed April 25, 1885. Serial No. 163,449. (No model.)

To all whom it may concern:

Be it known that I, JOSEPH HIRN, a citizen of the United States, residing at Chillicothe, in the county of Ross and State of Ohio, have 5 invented a new and useful Improvement in Car-Couplings, of which the following is a specification, reference being had to the accompanying drawings.

My invention relates to car-couplings, the 10 object being to provide a pivoted latch for supporting the link in a raised position and adapted to be struck by the link of the adjacent car to release the pin and effect a coupling.

15 A further object of the invention is to improve the details of construction, and to provide a coupling which shall be positive and effective in its operation, and one that will not be likely to get out of order.

20 With these ends in view the invention consists in the improved construction and combinations of parts hereinafter fully described, and pointed out in the claim.

25 In the drawings, Figure 1 is a front elevation of a car-coupling constructed in accordance with my invention. Fig. 2 is a section elevation showing the pin supported in a raised position, and Fig. 3 is a section of a modification.

30 In the accompanying drawings, in which like letters of reference indicate corresponding parts in all the figures, A represents the draw-head, which is provided with the usual link-opening, a, and pin-openings b, to receive 35 the coupling-pin B. The rear end of the opening, a in the draw-head is provided with a seat, d, in which the end of the coupling-link rests when the cars are coupled.

40 C represents an opening formed in the upper inner side of the draw-head just in rear of the upper opening, b, and having communication with said opening and with the link-opening, as shown at e.

45 In the opening C is located a latch, D, which is substantially segmental in form. The head

of this latch is slightly larger than the lower end of the opening C, so that when said latch drops to support the coupling-pin its end projects beyond the opening in the lower end of said opening C, and extends under the pin-opening b, thus supporting the pin. When the latch D is larger at its upper end than the opening C at its lower end, the said latch is introduced into the opening by providing an opening upon the upper side of the draw-head, which may, after the latch is in position in opening C, be closed, to prevent the latch from jumping out.

50 In the modification shown in Fig. 3 the latch is provided with an elongated slot, 60 through which passes a rod, f, thus pivoting said latch in the opening C, and allowing it a limited vertical movement.

55 In the operation of my invention the lower end of the pin rests upon the upper side of 65 the lower end of the coupling-latch. When the cars come together, the latch is struck by the link of the adjacent car, thus throwing it back into the opening C and releasing the pin, thus effecting a coupling.

70 Having fully described my invention, what I claim as new, and desire to secure by Letters Patent, is—

75 The combination, with a draw-head having the usual link and pin openings, and the opening C, smaller at its lower than at its upper end and located in the upper inner side of the draw-head, of a latch located in said opening, said latch being slightly curved and larger at its upper than at its lower end and located in the 80 opening C, and adapted to support the coupling-pin upon its lower end, substantially as set forth.

85 In testimony that I claim the foregoing as my own I have hereto affixed my signature in presence of two witnesses.

JOSEPH HIRN.

Witnesses:

E. K. MICK,
JOHN EWING.
